Des. 203,795
Patented Feb. 15, 1966

203,795

CENTER SET SHOWER FIXTURE

Homer M. Harvey, Los Angeles, and Dale H. Hart, Long Beach, Calif., assignors to Harvey Aluminum (Incorporated), Torrance, Calif., a corporation of California

Filed Nov. 2, 1964, Ser. No. 82,420

Term of patent 14 years

(Cl. D91—3)

FIG. 1.

FIG. 3

FIG. 2.

FIG. 4

FIG. 1 is a perspective view taken from the front, top and one side of the center set shower fixture embodying our new design.

FIG. 2 is a front view of the fixture.

FIG. 3 is a side view showing the other side of the fixture, and

FIG. 4 is a cross-sectional view disclosing the interior configuration of the panel portion of the fixture.

The dominant features of our design reside in the portions shown in full lines.

We claim:

The ornamental design for a center set shower fixture, as shown and described.
